William H. Paige, Inventor.
By L. A. Curtis, his atty.

United States Patent Office.

WILLIAM H. PAIGE, OF SPRINGFIELD, MASSACHUSETTS.

Design No. 4,541, dated December 27, 1870.

DESIGN FOR A RAILWAY-CAR-SASH LOCK.

The Schedule referred to in these Letters Patent and making part of the same.

To all whom it may concern:

Be it known that I, WILLIAM H. PAIGE, of Springfield, in the county of Hampden and State of Massachusetts, have invented and produced a new Design for a Railway-Car-Sash Lock; and I do hereby declare that the following is a full, clear, and exact description of the same, reference being had to the accompanying drawing making part of this specification, and to the letters of reference marked thereon, in which—

Figure 1 is a front view of the whole lock;

Figure 2 is a side view; and

Figure 3 is an end view.

The end pieces *b* are made thinner than the main part of the lock *a*, and they have the pointed parts *n n* on each end, one on each side, and the

curved part *o* between.

The curved piece *c* extends out at one side of the same thickness as the main part *a*, and this main part is curved at each end, as shown at *i*, and the projection *e* extends outward from the lever *d*.

Having described my invention,

What I claim as new, and desire to secure by Letters Patent, is—

The design for a railway-car-sash lock, herein shown in the drawing and described.

WILLIAM H. PAIGE.
